Patented Oct. 19, 1920.

FIG. 2

FIG. 1

Inventor
G. J. Reuter
By His Attorney
H. H. Dyke

UNITED STATES PATENT OFFICE.

GEORGE JOSEPH REUTER, OF ATLANTA, GEORGIA.

RUBBER HEEL.

1,356,113.

Specification of Letters Patent. Patented Oct. 19, 1920.

Application filed November 17, 1919. Serial No. 338,547.

To all whom it may concern:

Be it known that I, GEORGE JOSEPH REUTER, a citizen of the United States, and a resident of Atlanta, county of Fulton, and State of Georgia, have invented certain new and useful Improvements in Rubber Heels, of which the following is a specification.

My invention relates to rubber heels. A rubber heel in accordance with my invention has a rib or ribs projecting beyond the face thereof and containing reinforcing material adapted to prevent wear and slipping. Said ribs are adapted to be compressed when the weight is placed on the heel, and to return to original position when the weight is removed.

The reinforcing means preferably consist of layers of fabric extending substantially normal to the tread surface, and are preferably arranged around the nail holes. These portions of the heel are thus strengthened and the heel is firmly held in place when nailed on. Some or all of the reinforced parts or regions are also preferably connected together by reinforcing means embedded in the material of the rubber heel lift. For example, such cross-connecting reinforces preferably form substantially a semicircle about the rear of the lift, whereby the heel is strengthened and reinforced against wear at the region of greatest wear.

The object of my invention is the provision of a reinforced rubber heel having the features of advantage above referred to, and with the foregoing and related objects in view, my invention consists in the features, elements and combinations herein set forth and claimed.

In the drawings, Figure 1 is a bottom plan view with parts broken away, and Fig. 2 is a section taken on the broken line 2-2, Fig. 1.

The rubber heel 10 is provided with rings of reinforcing material as fabric 11, arranged about the holes 12 for the nails 13, formed adjacent to the heel periphery and by which the rubber heel is secured in place to the heel base 14.

The reinforcing material may be of various kinds and thicknesses. Three plies of fabric are illustrated. The reinforcing material 11, preferably extends at its inner edges to about the middle of heel lift 10 or at least terminate short of the attaching surface of the lift, and it projects beyond the bottom 15 of the heel, preferably about as

shown at 16, and about the projecting portion 16 the molded material of the heel 10 is extended to form substantially an annular rib 17, containing the projecting portion 16 of the reinforcing material. As the ring of reinforcing material is spaced away from the nail holes and nails which it surrounds, the nails are embedded in the mass of the rubber or rubber composition forming the body of the heel, which is continuous and uninterrupted. At the same time that portion of such rubber or composition about the nail head and within the ring of reinforcing material is compacted or held from spreading by the ring of reinforcing material.

Heels in accordance with the invention may simply have all or part of the nail holes surrounded with reinforced portions as described, but preferably I also provide projecting reinforced rib portions connecting some or all of the annular reinforces above described.

Such additional reinforced portions are preferably arranged at the back of the heel and, as shown, the front nail holes have the simple form of reinforces 18 and 19, while the side reinforced regions 20 and 21 are connected together and to the rear nail hole reinforced region 22 by the arcuate or crescent-shaped reinforce 23, contained in the raised molded rib 24 of substantially arcuate or crescent-shape. The extended arcuate portion 23 is preferably integral with the material of the connected rings of fabric.

A rubber heel in accordance with my invention has added resiliency and cushioning effect, as compared with the ordinary flat form of heel, since the projecting ribs are compressed more readily than the remaining flat part of the heel, giving a desirably good shock absorbing effect as the foot is put down, and this effect is increased by the reinforces not extending entirely to the attaching face of the lift, permitting compression and expansion of the rubber behind the reinforcing members. The reinforcing material of fabric or the like resists wear, so that the heel retains its symmetrical form and outline, and prevents the shoe being "down at the heel" for a very long time. The anti-slipping properties of the heel are very good; the projecting fabric edges being well distributed over the entire surface of the heel. The arcuate reinforce at the back of the heel is particularly effective in preventing the foot from slipping forward, as

when the heel is put down upon an icy pavement or the like.

It is to be understood that the construction illustrated is for affording an understanding 5 of my invention only, and not for limitation, and that modifications and changes may be made, within the scope of my claims, without departing from my invention or sacrificing the advantages thereof.

10 I claim:

1. A rubber heel lift having embedded therein a fabric reinforce comprising plies of fabric, normal to the tread surface, and of extended arcuate form, arranged at the 15 rear of the lift and having an end thereof coiled about a nail opening.

2. A rubber heel lift having embedded therein a fabric reinforce comprising plies of fabric, normal to the tread surface, and of

extended arcuate form, arranged at the rear 20 of the lift, and terminating at its opposite ends in rings coiled about separated nail openings in the lift.

3. A rubber heel lift having embedded therein a plurality of rings of fabric surrounding nail holes at the rear portion of the heel and connected by arcuate webs of fabric substantially integral with the rings, said rings and webs extending short of the attaching face of the lift and also extending 25 beyond the tread surface, and formed of a plurality of plies of fabric arranged normal to the tread surface.

In testimony that I claim the foregoing, I hereto set my hand, this 11 day of November, 1919.

GEORGE JOSEPH REUTER.
